UNITED STATES PATENT OFFICE.

WILLIAM M. STEVENSON, OF SPRINGFIELD, MASSACHUSETTS, ASSIGNOR TO HODGES FIBER CARPET COMPANY, OF SPRINGFIELD, MASSACHUSETTS, PORTLAND, MAINE, AND NEW YORK, N. Y., A CORPORATION OF MAINE.

WOVEN FABRIC.

SPECIFICATION forming part of Letters Patent No. 761,554, dated May 31, 1904.

Application filed July 22, 1901. Serial No. 69,270. (Specimens.)

To all whom it may concern:

Be it known that I, WILLIAM M. STEVENSON, a citizen of the United States, and a resident of Springfield, Massachusetts, have invented 5 certain Improvements in Woven Fabrics, of which the following is a specification.

My invention consists of a woven fabric especially designed for carpeting and containing weft-threads composed of strands or 10 fibers of wool, cotton, or like material spun into yarn and other weft-threads consisting of twisted strips of paper, the object of my invention being to provide a fabric which will possess desirable qualities of both a wool or 15 cotton fabric and a paper fabric and will also possess certain advantages over either of these fabrics.

In the accompanying drawings, Figure 1 is a face view of a piece of fabric made in accordance with my invention. Fig. 2 is an exaggerated section of the same, taken on the line *a a*, Fig. 1, or in the direction of the weft. Fig. 3 is an exaggerated section of the fabric, taken on the line *b b*, Fig. 1, or in the direction of the warp; and Fig. 4 is a view similar to Fig. 3, but illustrating another form of fabric embodying my invention.

The fabric shown comprises binding warp-threads 1 and 2 and heavier separator warp-threads 3, these threads being interwoven with two sets of weft-threads 4 and 5, the weft-threads 4 being composed of strands or fibers of wool, cotton, or like material spun into yarn and the weft-threads 5 consisting of strips 30 of twisted paper. The opposite faces of the fabric are formed by these weft-threads in substantially the same manner as the faces of an ordinary two-ply ingrain fabric, the weft-threads being disposed in upper and lower 35 planes and changing from face to face in accordance with the demands of the pattern. The warp-threads 3, however, in the fabric shown in the drawings simply act as separator-threads, the warp-threads 1 and 2 binding, first, 40 a weft-thread of one face and then a weft-thread of the other face, and the warp-threads 1 binding one face when the warp-threads 2 are binding the other face, as shown in Fig. 3,

so as to tie the two faces of the fabric firmly together and form a strong, well-tied, and homogeneous fabric. 50

The use of the paper weft-threads in connection with the wool or cotton weft-threads not only cheapens the fabric as compared with one using weft-threads composed entirely of 55 wool, cotton, or the like, but it has the further important effect of stiffening the fabric and giving it a firmer body than one composed entirely of wool, cotton, or like material, the stiff paper weft-threads rendering it unnecessary to bind the fabric at the usual close intervals, so that the fabric can be woven with half the quantity of binding warp-threads which would be required if the fabric was wholly of wool, cotton, or the like. The carpet, 60 moreover, possesses the advantage over one made wholly or largely of paper that it is warm enough for use during the winter season, and, if desired, the carpet may be made with all of the paper weft-threads on one face 65 and all of the wool or cotton weft-threads on the other face, as shown, for instance, in Fig. 4, the wool face being used uppermost during the winter season and the paper face being uppermost during the summer season, thus 70 combining in one fabric the advantages of both forms of carpet. 75

Although I prefer to use separator warp-threads 3 of a heavier character than the binding warp-threads, so as to act as stuffer-threads and give body to the fabric, this is not absolutely essential to the proper carrying out of my invention, as the warp-threads 3 would serve their function as separators whether coarse or fine. 80

Having thus described my invention, I claim and desire to secure by Letters Patent—

1. A woven fabric having binding warp-threads combined with weft-threads disposed in two planes, some of the weft-threads being 90 composed of wool, cotton, or the like, and the other weft-threads being composed of twisted strips of paper, thereby giving a firm body to the fabric and dispensing with the necessity of closely grouping the warp-threads, substantially as specified. 95

2. A woven fabric having binding warp-threads combined with weft-threads disposed in two planes with separator warp-threads between them, some of the weft-threads being composed of wool, cotton, or the like, and the other weft-threads being composed of twisted strips of paper, thereby giving a firm body to the fabric and dispensing with the necessity of closely grouping the warp-threads, substantially as specified.
3. A woven fabric having binding warp-threads combined with weft-threads disposed in two planes, having between them separator warp-threads heavier than the binding warp-threads, some of the weft-threads being composed of wool, cotton, or the like, and the other weft-threads being composed of twisted strips of paper, thereby giving a firm body to the fabric and dispensing with the necessity of closely grouping the warp-threads, substantially as specified.
4. A woven fabric having binding warp-threads combined with weft-threads disposed in two planes, the weft-threads of one plane being composed of wool, cotton, or the like, and the weft-threads of the other plane being composed of twisted strips of paper, substantially as specified.
5. A woven fabric having binding warp-threads combined with weft-threads disposed in two planes with separator warp-threads between them, the weft-threads of one plane being composed of wool, cotton, or the like, and the weft-threads of the other plane being composed of twisted strips of paper, substantially as specified.
6. A woven fabric having binding warp-threads combined with weft-threads disposed in two planes having between them separator warp-threads heavier than the binding warp-threads, the weft-threads of one plane being composed of wool, cotton, or the like, and the weft-threads of the other plane being composed of twisted strips of paper, substantially as specified.

In testimony whereof I have signed my name to this specification in the presence of two subscribing witnesses.

WILLIAM M. STEVENSON.
